(57) **CLAIM**

The ornamental design for a jewelry attachment cover for a set of earphones, as shown and described.

DESCRIPTION

FIG. 1 is a front perspective view of a left and right jewelry attachment cover for a set of earphones showing our new design;

FIG. 2 is a left top view thereof;

FIG. 3 is a left bottom view thereof;

FIG. 4 is a left front elevational view thereof;

FIG. 5 is a left rear elevational view thereof;

FIG. 6 is a left side elevational view thereof;

FIG. 7 is a right side elevational view of the left jewelry attachment cover for a set of earphones thereof;

FIG. 8 is a rear perspective view of the left and right jewelry attachment cover for a set of earphones thereof;

FIG. 9 is a right bottom view thereof;

FIG. 10 is a right top view thereof;

FIG. 11 is a right front elevational view thereof;

FIG. 12 is a right rear elevational view thereof;

FIG. 13 is a right side elevational view thereof; and,

FIG. 14 is a left side elevational view of the right jewelry attachment cover for a set of earphones thereof.

The broken lines shown in FIGS. 1 and 8 denote individual left and right monolithic ear pieces contained within each cover which are provided for illustrative purposes only and form no part of the claimed design; each monolithic ear piece has a front face and rear face surface with the noted circular vent openings and a downwardly extending tail member having connective wires.
